[57] CLAIM

The ornamental design for a game card scraper, as shown and described.

DESCRIPTION

FIG. 1 is a perspective view of a game card scraper showing my new design;

FIG. 2 is a front elevational view thereof, the rear view being a mirror image;

FIG. 3 is a left side elevational view thereof;

FIG. 4 is a right side elevational view thereof;

FIG. 5 is a top plan view thereof; and,

FIG. 6 is a bottom plan view thereof.

Undisclosed surfaces are plain and unornamented.
